UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed September 13, 1922. Serial No. 588,045.

To all whom it may concern:

Be it known that I, MANSFIELD C. CRAWLEY, a citizen of the United States of America, and a resident of Groton, county 5 of Tompkins, and State of New York, have invented certain new and useful Improvements in Typewriting Machines, of which the following is a full and clear specification.

10 The special object of this invention is to provide key-controlled power-operated means for actuating the carriage as well as the platen. The particular embodiment of the invention disclosed herein is especially 15 adapted for use in connection with the power-operated type-bar action disclosed in my former Patent, No. 1,156,061, dated October 12, 1915, in which a universal type-bar-actuator is actuated on its working 20 stroke by means of a spring and a continuously-running power-shaft is employed for retracting the actuator after each working stroke, latching devices being employed to hold the actuator back after it is retracted 25 and key-controlled means being employed for releasing said latch whenever a printing-key or space-key is actuated.

In the drawing—

Fig. 1 is a vertical sectional view of a 30 typewriting machine embodying my invention;

Fig. 2 is a vertical transverse sectional view looking rearward;

Fig. 3 is a perspective view of certain 35 essential mechanisms, the frame and some of the mechanisms of the machine being omitted for purposes of better illustration;

Fig. 4 is a detail front elevation of the essential parts of the carriage-return and 40 line-spacing mechanisms;

Fig. 5 is a vertical sectional view of the same;

Fig. 6 is a plan view in detail of the devices for locking the printing instruments;

Figs. 7, 8 and 9 are detail views especially intended to illustrate the carriage locking and unlocking devices;

Fig. 10 is a detail sectional view of the 50 carriage running gearing;

Fig. 11 is a front elevation, partly in vertical section, showing the paragraph-stop setting devices in normal position;

Fig. 12 is a detail front elevation, partly 55 in section, showing more particularly the

construction and arrangement of the carriage-stopping devices;

Fig. 13 is an inverted plan view, partly broken away, of the front part of the carriage;

Figs. 14 and 15 are detail perspective and sectional views, respectively, showing the central stop device on the machine frame.

Fig. 16 is a view similar to Fig. 12 showing the paragraph stopping means in action;

Fig. 17 is a perspective view of the left hand margin stop; and

Figs. 18, 19 and 20 are detail sectional views showing the paragraph stop, the left 70 hand margin stop and the right hand margin stop, respectively, in action.

Referring to the drawing annexed (8 sheets) by reference-numerals, 20 designates the fore-and-aft reciprocating universal curved type-bar-actuator which is supported on rock-arms depending from the rock shafts 10 and adapted to be thrown forward by a spring 11 to actuate the type-bars through push-couplers 21, a pull-back 80 link 22 and a crank-shaft 23 being employed for retracting the actuator against said spring 11. This crank-shaft 23 is journaled in bearings 12 and is provided with a stop-arm 24 which is adapted to engage 85 a spring-held stop 25 carried by a vertical latch-lever 26 pivoted at 27 in the machine frame, this latch-lever being connected by means of a link 28 to a curved universal release-bar 29 suspended on arms depending from a rock-shaft 13. A ratchet-wheel 30 is fixed on a shaft 31, which is continuously driven by a belt 32 driven by an electric motor 33. Shaft 31 is coaxial with shaft 23 and is journaled in bearings 14 on the machine frame. The release-bar 29 is adapted to be cammed backwardly by cam surfaces 34 on the push-couplers 21 when said couplers are raised through the medium of the push-bars 35 operated by the printing key-levers 15 of the machine. The rearward movement of the release-bar forces the lever arm of latch-lever 26 backwardly far enough to release the stop-arm 24 on crank-shaft 23, whereupon the spring 11 in the actuator 105 mechanism forces the type-bar-actuator forwardly to cause a printing operation.

At the proper moment, a pawl 36 pivoted on arm 24 is caused to engage in the teeth of ratchet-wheel 30, to thereby rotate shaft 110

22
 23 in a direction to retract the type-bar-
 actuator and cause it to be again latched
 in its rearward position, the latch-lever 26
 having meanwhile been forced forwardly to
 5 bring its stop 25 into the path of the arm
 24 by means of its actuating spring 37.
 The foregoing mechanism is fully disclosed
 in my co-pending case Serial No. 577,362,
 filed July 25, 1922, and therefore need not
 10 be further described herein.

The line-spacing mechanism disclosed
 herein is more fully disclosed in my co-
 pending application Serial No. 577,358,
 filed July 25, 1922, and I will, therefore,
 15 but briefly describe it herein. This mecha-
 nism embodies a driving friction clutch-
 disk 38 affixed to the aforesaid continuously-
 running shaft 31; a driven-friction disk 39
 20 loosely mounted on said shaft 31 which is
 in position to be frictionally engaged with
 the fixed member 38; a pivoted resilient lever
 40 for bringing about said engagement;
 and angular lever 41 for actuating the afore-
 25 said lever 40; and a key-lever 42 for actuating
 the levers 41 and 40 to press clutch disk
 39 against clutch disk 38. Affixed to the
 free clutch-member 39 is a pinion 43, and
 held in constant engagement with this pinion
 30 is a segment 44 which is provided with a
 pair of depending stop-arms 45 at which
 also is connected by a pivotal link 46 to a
 depending rock-arm 47, this arm 47 being
 affixed to one end of a sheet-metal rock-shaft
 35 whose opposite end is provided with an
 upwardly-extending arm 49 adapted to
 have constant engagement with a swinging
 frame 50 mounted on the carriage. The
 frame 50 carries an upstanding arm 51
 40 which at its upper end is pivotally connect-
 ed to a line-spacing pawl 52. With this con-
 struction, it will be observed that the de-
 pressions of the line-spacing lever 42 will
 45 put the friction clutch into action and thus
 swing the lower end of the depending lever
 47 forwardly through the medium of the
 segment 44 and the link 46; this will, as is
 obvious, cause a line-spacing action of the
 50 platen through the rotation of the line-space
 ratchet-wheel 16 by pawl 52. A spring 53
 returns the parts to normal position as soon
 as the operator frees the clutch by releasing
 the key-lever 42.

The opposite face of the fixed or driving
 55 clutch disk 38 is utilized for actuating the
 case-shift mechanism. For this purpose, I
 provide another loose disk 54 similar to the
 disk 39 and having affixed to it a pinion 55
 in constant engagement with a segment 56
 60 similar to segment 44. A resilient clutch-
 actuating lever 57 is provided which lever
 is formed of resilient metal and adapted to
 be actuated by an angle-lever 58 through
 the medium of a shift key-lever 59 to press
 the disk 54 against disk 38.

65 When the shift key-lever 59 is depressed,

the clutch-members 54 and 38 will be fric-
 tionally engaged, and, through the medium
 of pinion 55 and its meshing segment 56, a
 case-shift action will take place, said seg-
 ment operating a crank mechanism 17
 70 through a link 18 to lift the platen support-
 ing shift frame 19, as more fully shown and
 described in my copending application Se-
 rial No. 577,357, filed July 25, 1922, said
 shift frame moving up and down in the
 75 rectangular frame 119 of the platen car-
 riage and partaking of the transverse move-
 ment of the carriage along the guide rails
 120 and 90 on the machine frame 121.

The carriage is provided with a rack-bar
 80 60 which extends the length of travel of the
 carriage and is in constant engagement with
 a pinion 61 affixed to the upper end of a
 vertical shaft 62 journaled in a bearing 122
 on the machine frame and whose lower end
 carries a bevel-pinion 63. Meshing with this
 bevel-pinion 63 are two bevel-gears 64—65
 85 loosely mounted on the aforesaid driving-
 shaft 31. Fixed to the outer faces of gears
 64 and 65 are conoidal clutch members 123.
 Friction clutch disks 66 are affixed to the
 shaft 31 in sufficiently close proximity to the
 outer faces of members 123 to ensure a fric-
 tional driving engagement between the com-
 90 panion clutch members when gears 64 and
 65 are pressed slightly outwardly without
 de-meshing from pinion 63. A pair of re-
 silient levers 67—68 are pivoted at 124 on
 the machine frame below the gears and they
 have their forked upper ends, respectively,
 positioned to engage the inner faces of the
 95 respective gears 64—65, so that when the de-
 pending resilient end of either lever 67—68
 is swung inwardly, the loose clutch mem-
 ber 123 fixed to the loose gear engaged by
 the lever will be frictionally engaged with
 100 its companion driving clutch member 66 and
 be thereby rotated. With this simple mech-
 anism, it will be observed that the carriage
 may be given a running movement in either
 105 direction, to thereby permit the carriage to
 be rapidly advanced or rapidly returned to
 starting point.

For actuating the left-hand clutch-lever
 110 68 (to advance the carriage), I provide a
 transverse sub-lever 69 pivoted intermediate
 its end at 125 on the frame and adapted to
 be swung upwardly by the rear-end of the
 advance-key-lever 70 to cause the inner end
 115 of the sub-lever to press inwardly against
 the lower end of clutch lever 68. The inner
 end of the lever 69 is curved outwardly upon
 itself to provide an outwardly-downwardly
 facing cam edge 71 for a purpose herein-
 after described. For actuating the carriage-
 return clutch-lever 67, I provide a trans-
 verse sub-lever 72 pivoted at 126 on the ma-
 chine frame and whose outer end is adapted
 120 to be swung upwardly by either the key-
 lever 73 or the key-lever 113, said sub-lever
 125

- 72 being provided with an arm 72^a for operating clutch lever 67 and an inwardly-extending arm 74 adapted to depress an arm 75 extending inwardly from the aforesaid 6 line-space sub-lever 41, whereby when either of the key-levers 73 and 113 is actuated to return the carriage, there will be a simultaneous operation of the line-spacing mechanism, as shown in Fig. 4.
- 10 The letter-feed movement of the carriage is accomplished through the same pinion (61) which is employed to give the carriage a running movement. This letter-feed mechanism is fully disclosed in my co-pending 15 application Serial No. 588,046, filed September 13, 1922. It consists generally of a star-wheel 75 affixed to the shaft 62 and adapted to be stepped around by means of a pair of pawls 76—77 to advance the carriage 20 in letter-feed direction through pinion 61 and rack 60. The pawls are adapted to be reciprocated through the medium of the movement of the type-bar-actuator 20, pivotal links 78 being employed for connecting 25 the pawl-carrying arms 127 to the actuator to swing said arms about the axis of shaft 62. It is sufficient in this case to state simply that normally pawl 77 is out of engagement with the feed star-wheel, while the 30 companion pawl 76 normally engages in one of the notches of the wheel (as shown in Fig. 9) and thereby serves to lock the carriage against movement in either direction. It will be understood that the letter-feeding 35 of the carriage is not accomplished through the power driving gears 63—64—65, but solely through the action of the type-bar-actuator and the connected mechanism above briefly described. During letter-feed of the 40 carriage, both the drive-gears 64—65, altho in mesh with the bevel-pinion 63, are out of driving connection with their respective clutch members 66, thereby leaving the pinion-shaft 62 free to be rotated by the letter-feed. Briefly, the carriage is fed one-half 45 letter-space by pawl 76 on the forward stroke of the actuator 20 which pulls forward by a hook 128 a lever 129, this lever being pivoted on the actuator at one end and links 50 78 being pivoted at their forward ends to the other end of this lever 129. Lever 129 is caused to move rearward on the return stroke of the actuator by the stiff spring 130 to cause pawl 77 to feed the carriage 55 another one-half letter space. A plate or shield 131 controls the action of the pawls on the wheel 75.
- It will be obvious that whenever the carriage is given a running movement in either 60 direction, it is essential that the locking pawl 76 be disengaged from the star-wheel 75 to permit the star-wheel to rotate with the shaft 62. For this purpose, I pivot on the shaft 62 a short escapement-release lever 65 79 in position to have one of its arms engage pawl 76 and its other arm to be engaged by the upper arm of a vertical lever 80 pivoted at 132 on the machine frame, the lower end of said lever 80 having a laterally-bent lug 81 adapted to be engaged by the aforesaid 70 cam edge 71 on lever 69 when lever 69 is actuated by the advance-key lever 70. In this way, it will be observed that when the advance-key is actuated, as shown in Figs. 7 and 8, to give the carriage a running 75 movement toward the left, or in letter-feed direction, the levers 80 and 79 will cam the pawl 76 out of engagement with the star-wheel 75 and hold it out so long as the advance-key on key-lever 70 is held depressed by the operator. By mechanism hereinafter described this carriage-locking pawl 76 will also be unlocked when the combined carriage-return and line-space key-lever 73 or the combined paragraph-stop control, carriage return, and line-space key-lever 113 is actuated, to thereby permit the carriage to be returned by a running movement toward the right.
- In addition to unlocking the letter-feed 80 whenever the carriage is given a running movement, it is desirable also that the printing instrumentalities be locked against actuation, this being particularly desirable in a machine where, as in the present instance, the printing mechanism is designed to be put into action by as light a touch as is feasible. For this purpose, I employ a locking-bar 82 slidably guided on the frame, to move 85 horizontally, at a point where, when it is moved to the right, it will lie in front of the latch-lever 26 at a point above its pivot 27 and thus lock the latch-lever against actuation by the universal release-bar 29. The locking bar 82 is held in place and guided 90 on the frame by pin-and-slot connections 83, and is provided with a pair of lugs 84 which are so positioned as to engage opposite edges of the upper end of the before-described lever 80, so that when the upper end of said lever 80 is swung to the right by means of the advance-key lever 70 and sub-lever 69, the bar 82 will be pushed into locking position and be held there while the advance key 95 is held down, i. e., until the advance movement of the carriage is completed. It is desirable also to bring about this locking operation whenever the carriage is manually run back or forth; I accomplish this by attaching to the depending line-spacer rock-arm 47 a link-bar 85 whose rear end is provided with a cam-edge 86 adapted to impinge against an upstanding lug 87 on the bar 82, the arrangement being such that when the link-bar 85 is pulled forward, the locking-bar 82 will be cammed into locking position, as shown in Fig. 6. This movement to the right of the bar 82 by the link 100 85 performs another function as hereinbefore described, to wit, actuation of the car-
- 105 110 115 120 125 130 135

riage-unlocking lever 79 through lever 80, to thus release the carriage from the letter feed or escapement devices. Link-bar 85 is slotted at its rear end and guided on a member 133 rigid on the machine frame.

The forward swinging of the depending lever 47 is accomplished manually by swinging rearwardly the upper end of the arm 51. This movement of the line-spacing mechanism need not cause a line-spacing action, as, by tilting the pawl 52, the tooth of the pawl may be lifted out of engagement with the platen-ratchet; for conveniently doing this I provide a finger-piece or manual carriage-release key 88 on the rearward-projecting end of the pawl, which finger-piece may, of course, be employed also for pulling back the arm 51 simultaneously with the throwing out of the line-space pawl. In this connection, it will be understood that the arm 49 has constant interlocked connection 134 with the line-spacing rail 89, which extends the full length of travel of the carriage, so that the release of the carriage-lock and the actuation of the lock bar 82 may be accomplished at any point in the travel of the carriage; and it will be understood also that the forward swinging of the lever 47 by key 88 produces merely an idle operation of the segment 44 and its associated pinion 43 and loose clutch-member 39.

It will be observed also that by attaching the link 85 to a member (preferably lever 47) of the line-spacing mechanism, I provide thereby for unlocking the letter-feed and locking the type-bar-actuator through the medium of the line-space mechanism whenever the carriage-return lever 73 or the paragraph-key-lever 113 is actuated, since, it will be remembered, actuation of either one of these levers automatically and simultaneously puts into operation the power-driven line-spacing mechanism through the medium of the lever arms 74, 75.

For stopping the running of the carriage in its advance movements as well as in its return movements, I employ the following devices: I attach to the underside of the front guide rail 90 for the platen carriage 119, which rail is fixed on the machine frame parallel with and adjacent to a scale plate 91 on the front transverse member of the carriage, a flat spring 92 preferably composed of two leaves, the left-end of this spring being rigidly anchored to the guide rail 90 at 135 and the right-end being free to flex away from the bottom side of the rail. Mounted on the front face of the rail 90 is a rocking-bar 93, this rocking bar being secured to the rail midway the travel of the carriage by means of a pivot 94 anchored in the front face of the rail. This bar-like member 93 has its under edge resting upon or closely adjacent to the upper side of the spring 92 adjacent the free end of said

spring, so that when the bar is rocked on its pivot 94, one horizontal arm or the other thereof will be swung downwardly to thus cause the spring to be flexed downward against its normal tendency to lie flat against the under face of rail 90. The arm of this rocking member which extends toward the free end of the spring 92 is longer than the other arm, to compensate for the fact that it engages the spring at a more distant point from the fixed end thereof than is engaged by the other arm, whereby the leverage exerted to flex the spring is approximately the same whichever way the rocking member is rocked. This rock-bar 93 is provided, at a point coincident with its pivoted point, with an upstanding arm 95 which is adapted, through a tappet or centrally located arresting device 107 (hereinafter described), to receive the thrust of the stops on the carriage, hereinafter described; and it will be observed that, whether the thrust on this arm 95 be from the right or the left, the result will be to cause the rocker to slightly flex the spring 92. In this way, I provide for effectively cushioning the jar incident to arresting the carriage, whereby I greatly reduce noise and vibration of the machine parts. Thus cushioning the carriage is, of course, desirable only when the carriage is given a running movement to its stopping point, since, when the carriage is fed for letter-spacing, its feed or escape-ment means will effectively control its movement.

The carriage-return or left-hand margin-regulating stop 96 comprises a main flat sheet metal body-portion provided at one end with a forwardly extending lug 136 to which is pivoted at 137 a bell-crank locking and adjusting lever 98 having its short forwardly extending arm connected by a spring 138 with a forwardly extending stop-lug 99 at the opposite end of the flat body portion of the stop adapted for engagement with the part 107^a of the aforesaid tappet 107 on the buffer rocker 93-95. The transversely extending long arm of lever 98 is provided with a vertical arm or finger-piece 100 which extends up through a slot 139 formed in the front cross member of carriage 119 parallel with and adjacent the upper edge of scale plate 91. The arm 100 is bent downwardly and forwardly and formed into a pointer 101 which lies adjacent to the graduations on the scale-plate, to thereby permit the pawl to be manipulated and the stop to be adjusted to the desirable scale point. Arm 100 is formed with a rearwardly and downwardly extending locking lug or projection 141 adapted to engage in notches in the forward edge of a transverse bar 97 rigidly supported under the front cross member of carriage 119 and spaced therefrom by suspending means 140, said bar being parallel with slot 139.

139. The carriage-advance arresting stop 102 is constructed similarly to the return-stop 96, except that its stop-lug 103 is constructed and positioned during letter-feed to impinge and ride upon the stepped upper edge of a pivoted lever 104, for the purposes set forth in my co-pending application Serial No. 592,525, filed October 25, 1922.

When the carriage is given a running movement in advance direction, the stepped lever 104 is pushed down out of the way by the lower end of stop lug 103 to thereby permit stop-lug 103 to directly strike the part 107^a of the stopping tappet 107, to thereby bring the cushioning spring 92 into action and arrest the carriage 119.

The foregoing carriage-arresting stop devices serve to arrest the carriage at the extreme ends of its predetermined transverse movement. It is desirable at times to arrest the return movement of the carriage at a point short of that for which the left-hand margin stop 96 is adjusted, as, for instance, where it is desired to arrest the return of the carriage in position to start a new paragraph. For this purpose, I provide another adjustable stop 105 on the rack-bar 97, this paragraph stop being constructed similarly to the other stops hereinbefore described,

30 except that its stop-lug 106 is in a plane sufficiently lower than the stop-lug 99 on the return-stop 96 to permit it to normally pass under the part 107^a of the stop-tappet 107. Tappet 107 is vertically slidable on arm 95, the screw 94 passing through a slot 142 in the tappet and said arm 95 having its reduced upper end extending through an aperture 143 in part 107^a of the tappet. When the tappet is lowered slightly, part 107^a will

40 lie in the path of the aforesaid paragraph-stop lug 106 and receive the thrust of the stopping movement thereof and transmit that thrust to the arm 95 of the thrust-receiving rocker. This stop-tappet is adapted to be lowered into operative position by means of the aforesaid lever 104, which lever supports this stop-tappet in its up position by means of a lug 108, the lever 104 being normally held up by a spring herein-

50 after described. The lever 104 is pivoted to the rail 90 at 144 near the left side of the machine frame 121 and extends to a point near the opposite side of the frame, its free end 109 being bent so as to lie underneath the top of the main frame. Loosely engaged under said free end 109 of lever 104 is the forward end of a vertically swinging lever 110 pivoted on the frame at 145, and pivotally connected to this lever 110 at 146 is a

60 depending link 111 to the lower end of which is connected the upper end of a rod-link 112, whose lower end is pivotally connected to the paragraph-key lever 113. When the key on the paragraph-key lever 113 is depressed the free end of the stepped lever 104 will be

pulled down against the the action of a coil-spring 114 and remain down only so long as the paragraph-key is held depressed. Spring 114 connects link 111 with the machine frame and normally holds said link and levers 110 and 104 up so as to hold the gravity tappet 107 up. It will thus be seen that by depressing the key on the paragraph-key lever 113, the paragraph stop-lug 106, when the carriage is given a running movement in return direction, will strike against the tappet 107 and thus stop the carriage, with a cushioning effect, at the point set for a new paragraph. By arranging this paragraph-key 113 to engage sub-lever 72, it will be observed that its operation will render the paragraph-stop effective and also put into action at the same time the carriage-return mechanism and the line-spacing mechanism, it being remembered that the operation of the line-spacing mechanism in this manner brings about not only a locking of the printing instrumentalities but also unlocking of the carriage feed.

It will be observed also that if, as usual, the paragraph is to be started with a capital letter, the platen-shift key-lever 59 may be operated at the same time key-lever 113 is operated, to thereby bring about simultaneously a fourfold preparatory operation of the machine, i. e., carriage-return, paragraph-stop, line-spacing, and case-shift, the construction being such that all these operations are performed by power taken from a single continuously-running power-shaft.

With regard to the stop-tappet 107, it will be observed that it normally rests upon the upper edge of the lever 104 and that it falls with said lever by gravity when said lever is lowered. A suitable spring, however, may be employed for ensuring prompt downward movement of the tappet when the lever 104 falls. This stop-tappet 107 is desirably formed of a piece of sheet-metal whose upper end is bent rearwardly and then upwardly and provided with the hole 143 up through which the upper reduced end of the thrust-lug 95 passes, this reduced end together with pivot 94 serving to guide the tappet in its vertical movement. In its

normal position, as stated, the upper angular portion 107^a of the stop-tappet 107 is in horizontal alinement with the stop-lug 99 on stop 96 and out of alinement with paragraph-stop-lug 106, so that said paragraph-stop lug 106 will pass underneath the rearwardly bent part of the tappet without striking the same and to the rear of the thrust-lug 95, until the tappet is lowered by the paragraph-key. The stops 96, 102 and 105

120 are each provided with a channel front flange 147 and a channel rear flange 148 for slidably supporting and guiding the stops on bar 97. Each of said stops is adjustable along the bar by pulling forward on finger-

piece 100 until nose 141 leaves the notch engaged thereby and abuts against a stop shoulder 149 on the stop, whereupon the finger-piece is moved along slot 139 until 5 pointer 101 is at the desired position and is then released.

It will be understood that the friction-clutches I employ in the line-spacing mechanism and case-shift mechanism permit a 10 slipping action after line-spacing operations and case shift operations are completed. The same slipping clutch action is provided in the gearing 64, 65 for giving the carriage a running movement. This slipping of the 15 clutches is particularly advantageous in a machine of this character where the case-shift actions, the line-spacing actions, and the carriage-running actions are completed at different times and before the operator 20 releases the key. In this way, all jars and injurious jamming strains on the power mechanism are eliminated, and this result is materially promoted by making the depending portions of the clutch-actuating levers 40, 57, 68, 67 slightly resilient and also, 25 of course, by providing the usual stop for the key-levers which actuate said clutch-levers, these key-lever stops serving to prevent any excess of pressure being put on the 30 slip clutches. In this connection, it will be observed that the carriage-running gears 64, 65 are in constant mesh with the driven-gear 63 and that, therefore, these driven-gears 64, 65 will receive an idle rotation during 35 letter-feeding. By thus arranging the gears 64, 65 to have constant mesh with the driven-gear 63, it will be observed that I avoid the trouble that might ensue by meshing and demeshing the gears with each operation. 40 The gears 64, 65 are held in constant mesh with the driven-gear 63 by so positioning the driving members 66 of the clutches that there is insufficient space to permit the gears 64, 65 to be disengaged from the driven-gear 63 even when the clutch members 123 held 45 to said gears are pressed closely in engagement with said clutch-members 66. It will be understood also that when the clutch associated with either one of these gears 64 or 50 65 is in clutched relation the other one of said gears receives an idle rotation. To ensure a delicate and yet sufficient frictional engagement, I make the metallic loose clutch members 123 in the form of conoidal cups to 55 adapt said members to engage the conical peripheries of their companion clutch-disks 66, these clutch-disks 66 being desirably made of fiber. The loose clutch disks 39 and 54 of the line-spacing and case-shift clutches, 60 respectively, are similarly formed, and the intermediate duplex cone clutch-member 38 is like-wise desirably made of fiber material. These friction-disks 39 and 54 and 123 are desirably radially slotted at 118, to 65 thereby provide scraping edges which work

lightly on the conical periphery of the fiber disks to thereby keep the same scraped clean of oil and dust, and thus ensure an effective operation of the clutches even after long usage of the machine. 70

As it is under certain conditions desirable that the carriage should be returned or partly returned without line-spacing the platen, I provide a key-lever 150 adjacent the key-lever 73 for this purpose. Said key-lever 150 engages under the outwardly extending arm of a transverse sub-lever 151 at a point beyond the end of sub-lever 72 so as to operate only the sub-lever 151. This arm of lever 151 is preferably offset from 80 the outwardly extending arm of lever 72 so lever 151 will not be actuated by key-levers 73 and 113, the sub-levers 72 and 151 being mounted side by side on the same pivot 126. Lever 151 has an upwardly extending arm 85 152 for operating the carriage-return clutch-lever 67, and is also provided with an arm 153 having a cam edge 154 adapted to ride over the lug 81 at the lower end of lever 80 to actuate the carriage-release lever 79 and 90 the type-bar-actuator lock 82. It will thus be seen that key-lever 150 operates the carriage-return clutch, the escapement-release, and the lock for the printing mechanism, but does not operate the line-space mechanism as 95 sub-lever 151 has no arm corresponding with arm 74 of sub-lever 72. 100

A spring 155 connecting release lever 79 with a fixed part on the machine frame serves to restore said lever, the slide 82, and lever 80 to normal position after all operations of said parts in the several ways hereinbefore described. A spring 156 connecting the clutch levers 67 and 68 serves to yieldably hold said levers in normal release position, and this spring 156 and spring 155, above described, serve to assist the weight of the long outwardly extending arms of the transverse sub-levers 69, 72 and 151 to promptly restore the sub-levers to normal 110 position when the key-levers are released. 105

A pawl controller 157 pivoted on the carriage at 158 serves to hold the pawl 52 normally out of the ratchet 16, said pawl riding up over the laterally bent upper end of the controller 157 as it returns to its normal forward position, shown in Figs. 1 and 2. When the pawl is pulled rearwardly it drops into the ratchet. When the controller is in its forward position, shown, the pawl will rotate the ratchet two-tooth spaces before striking stop 159 on the carriage. The controller is adjustable rearwardly about its pivot to a point where it will hold pawl 52 out of the ratchet until it moves back far enough to drop into the first ratchet tooth forward of stop 159, thus causing a single-space rotation of the platen. 115 120 125

The escapement mechanism may be reversed or adjusted to feed the carriage in 120

the return direction, toward the right, by swinging the cam plate 131 to a position in which pawl 76 is normally out of engagement with wheel 75 and pawl 77 is in one of the notches in said wheel. This reverse feed is more fully shown and described in my co-pending case Serial No. 588,046, filed Sept. 13, 1922, above referred to, and is desirable for printing from right to left or for back-spacing the carriage without printing.

The cam plate 131 is adjusted to reversing position by a back-space key lever 160. When the key on this lever is depressed the lever pushes up a link 161, which rocks a plate 162, pivoted at 163 on the frame, in a direction to push a link 164 toward the left. Link 164 is connected at its inner end to the rearwardly extending arm of cam plate 131. Movement of the parts just described is limited by a stop pin 165 engaging in a slot in plate 162. The reversing means is restored by a spring 166 when the back space key is released. The actuator 20 may be tripped to feed the carriage, when key lever 160 is actuated, by operation of any of the type keys, or it may be tripped by the space bar as shown in Serial No. 588,046, filed September 13, 1922, above referred to.

3. In a typewriting machine, the combination of a carriage, key-controlled power-driven means operable from a continuously-running power-shaft for running said carriage toward the right-hand side of the machine, and power-driven platen rotating mechanism operable independently from the same power-shaft simultaneously with and through the same key that controls the carriage running means.

4. In a typewriting machine, the combination of a carriage, a rack thereon, a carriage drive shaft, a pinion on said shaft engaging said rack, a continuously operating main shaft, key-actuated means for connecting the main shaft to the carriage drive shaft to move the carriage in one direction, line-spacing means operable from said main shaft, means whereby the said key will operate said line-spacing mechanism to cause it to operate simultaneously with the carriage moving means, and an independent key for independently operating the line-spacing mechanism.

5. In a typewriting machine, the combination of a carriage, a continuously-running power-shaft, key-controlled power means operable from said shaft for giving a running movement to said carriage toward the right-hand side of the machine to thus return the same to starting position, independent platen-rotating mechanism operable from the same power shaft to rotate the platen one line-spacing step and operable through the same key that controls the carriage-moving means, and an independent key for independently operating the line-spacing mechanism.

6. In a typewriting machine, a frame, a platen carriage, an adjustable margin stop on the carriage, an adjustable paragraph stop on the carriage, a cooperating tappet centrally located on the frame normally in the path of the margin stop and out of the path of movement of the paragraph stop, power means for returning the carriage, and a single key for moving said tappet into the path of said paragraph stop and putting the carriage-returning means into action.

7. In a typewriting machine, a frame, a platen carriage movable transversely of the frame, an adjustable paragraph-stop on the carriage, a cooperating tappet on the frame normally held up out of the path of said stop, and key-actuated means for lowering said tappet into the path of said stop, said tappet being slidably mounted upon a thrust lug.

8. In a typewriting machine, a frame, a platen carriage movable transversely of the

riage-returning mechanism operable from the same key and embodying a resilient lever and a friction slip-clutch actuated thereby.

the return direction, toward the right, by swinging the cam plate 131 to a position in which pawl 76 is normally out of engagement with wheel 75 and pawl 77 is in one of the notches in said wheel. This reverse feed is more fully shown and described in my co-pending case Serial No. 588,046, filed Sept. 13, 1922, above referred to, and is desirable for printing from right to left or for back-spacing the carriage without printing.

The cam plate 131 is adjusted to reversing position by a back-space key lever 160. When the key on this lever is depressed the lever pushes up a link 161, which rocks a plate 162, pivoted at 163 on the frame, in a direction to push a link 164 toward the left. Link 164 is connected at its inner end to the rearwardly extending arm of cam plate 131. Movement of the parts just described is limited by a stop pin 165 engaging in a slot in plate 162. The reversing means is restored by a spring 166 when the back space key is released. The actuator 20 may be tripped to feed the carriage, when key lever 160 is actuated, by operation of any of the type keys, or it may be tripped by the space bar as shown in Serial No. 588,046, filed September 13, 1922, above referred to.

In this case I make no claims for the case-shift mechanism separately, as that mechanism is specifically covered in my co-pending application Serial No. 577,357, filed July 25, 1922. In this case I make no claims for the line-spacer separately, as that mechanism is specifically covered in my co-pending application Serial No. 577,358, filed July 25, 1922. In this case I make no claims for the type-bar action, as that mechanism is specifically covered in my co-pending application Serial No. 577,362, filed July 25, 1922. In this case I make no claims for the carriage-feeding mechanism, as that mechanism is specifically covered in my co-pending application Serial No. 588,046, filed September 13, 1922.

What I claim is:

1. In a typewriting machine, a continuously-driven power-shaft, key-controlled means for operating the line-spacing mechanism of the machine from said shaft embodying a slip-clutch adapted to be put into action and held in action by the key, and a carriage-returning mechanism adapted to be put into action by the same key simultaneously with the line-spacing mechanism and also embodying a slip-clutch adapted to be put into action and held in action by the key.
2. In a typewriting machine, a continuously-driven power-shaft, key-controlled means for operating the line-spacing mechanism of the machine from said shaft embodying a friction-clutch and a resilient lever for putting the same into action and holding it in action, and key-controlled car-

frame, power means for giving the carriage a return running movement, a paragraph stop on the carriage, a paragraph-tappet on the frame normally out of the path of said stop, and key-controlled means for shifting said tappet into the path of the paragraph-stop and also putting into action said carriage-running means, said tappet being slidably mounted on a vertical cushioned thrust lug.

9. In a typewriting machine, a frame, a platen carriage movable transversely of the frame, a paragraph-stop on the carriage, a cooperating tappet on the frame, a carriage-return mechanism, a line-spacing mechanism, a case-shifting mechanism all of said mechanisms being capable of operating simultaneously, and key means for putting said mechanisms into action and shifting said tappet into the path of the paragraph-stop.

10. In a typewriting machine, a frame, a platen carriage movable transversely of the frame in either direction, an adjustable paragraph-stop on the carriage, a margin return-stop on the carriage out of alinement with said paragraph-stop, tappet means on the frame for engaging either one of said stops according to its adjustment, and key-controlled means for adjusting said tappet means to cooperate with either one of said stops, said tappet being mounted to slide vertically on an oppositely-tiltable cushioned thrust lug.

11. In a typewriting machine, a frame, a platen carriage movable transversely of the frame in either direction, a paragraph-stop on the carriage, a margin return-stop on the carriage located at a point to the left of the paragraph-stop and out of alinement therewith, tappet means on the frame for cooperating with either one of said stops and normally set to co-act with the margin stop, and key means for setting said tappet means to cooperate with the paragraph stop, said tappet being mounted to slide vertically on an oppositely-tiltable cushioned thrust lug.

12. In a typewriting machine, a frame, a platen carriage movable transversely of the frame, a paragraph-stop on the carriage, a margin return-stop on the carriage to the left of said paragraph-stop and out of alinement therewith, stopping means on the frame for cooperating with either one of said stops embodying a cushioned thrust member, a tappet normally out of alinement with the paragraph-stop, and key means for adjusting said tappet into the path of said paragraph-stop, said tappet being associated with the thrust member so as to communicate thrust thereto when either stop strikes the tappet.

13. In a typewriting machine, a frame, a carriage movable transversely of the frame carrying a margin-stop and also a para-

graph-stop, a cushioned thrust-lug on the frame, a vertically slidable tappet slidably mounted on said thrust lug, means for normally holding this tappet up out of the path of the paragraph-stop and into the path of the margin-stop, and key means for lowering said slidable tappet into active position for the paragraph stop.

14. In a typewriting machine, a frame, a carriage movable transversely of the frame, margin-stops on the carriage, a cooperating tappet centrally located on the frame of the machine, an oppositely-tiltable thrust lug carrying said tappet, and spring buffer means for said thrust lug.

15. In a typewriting machine, a frame, a carriage movable transversely of the frame, margin-stops on the carriage, a cooperating tappet centrally located on the frame of the machine, and spring buffer means for said central tappet embodying a flat spring and two oppositely-projecting arms connected to the tappet.

16. In a typewriting machine, a frame, a carriage movable transversely of the frame, power means for giving the carriage a running movement in either direction, margin-stops on the carriage, a central pivoted tappet structure on the frame for receiving the thrust of both of said stops and thus arresting the carriage, and spring buffer means arranged to permit said tappet structure to yield in either direction according to which stop strikes it.

17. In a typewriting machine, a frame, a platen carriage movable transversely of the frame, power means for giving the carriage a running movement in either direction, margin-stops on the carriage, a central pivoted tappet-means on the frame for receiving the thrust of either of said stops and thus arresting the carriage, and spring buffer means arranged to permit said tappet-means to yield in either direction according to which stop strikes it, said buffer means embodying a flat spring and a pair of arms forming part of said tappet-means.

18. In a typewriting machine, a platen carriage, means for feeding the carriage embodying a pinion shaft carrying a notched feed-wheel and a feed dog normally engaging said wheel to thus serve as a carriage-lock, key-controlled means for giving the carriage a running movement through said pinion shaft, and devices automatically actuated thereby for unlocking the carriage by disengaging said feed dog from its notched wheel.

19. In a typewriting machine, a platen carriage, key-controlled power-actuated means for giving the carriage a running movement, power-actuated carriage-feed devices operable through a part of said carriage-running means embodying a carriage-lock, and means for unlocking the carriage.

automatically when the carriage-running means are put into action.

20. In a typewriting machine, a platen carriage, reciprocating power-actuated means for actuating the printing instrumentalities, power-actuated means for giving the carriage a running movement, key-controlled devices for putting either of said means into action, and a locking device for the printing instrumentalities automatically actuated into locking engagement with said reciprocating power-actuated means when the carriage-running devices are put into action.

21. In a typewriting machine, the combination of a platen carriage, escapement mechanism for imparting letter-space movements to the carriage, means for releasing the carriage from the escapement mechanism, a keyboard key for actuating said releasing means, power means controlled by said keyboard key for imparting running movements to the carriage, a power line spacing means, and a key on the carriage operatively connected to actuate said releasing means independently of said power carriage-running means and through said line-spacing means.

22. In a typewriting machine, the combination of a platen carriage, a platen on the carriage, escapement mechanism for imparting letter-space movements to the carriage, printing means, locking means adapted to lock the printing means out of action, a keyboard having printing keys for controlling the printing means and a control key for actuating said locking means to lock the printing means, a key on the carriage operatively connected to release the carriage from the escapement mechanism and actuate said locking means, and means under control of said control key in the keyboard for returning the carriage and rotating the platen for line-spacing.

23. In a typewriting machine, the combination of a power-actuated type-carrier-actuator, a platen carriage, a platen on the carriage, escapement mechanism for letter-spacing the carriage, type, a keyboard having keys for controlling the type, a carriage-release key on the carriage, means operable by said carriage release key for releasing the carriage from the escapement mechanism for running movement by hand, and means operable by said carriage-release key for locking said actuator and thus preventing printing movements of the type under control of the keyboard keys when the carriage is released from the escapement mechanism.

24. In a typewriting machine, the combination of a continuously running power-shaft, a platen carriage, a platen on the carriage, letter-spacing mechanism for the carriage, printing means, power-operated means for returning the carriage, power-operated line-spacing means for rotating the platen,

a key for connecting both of said power-operated means with said continuously running shaft, and a key for connecting only the line-spacing mechanism with the said shaft.

25. In a typewriting machine, the combination of a continuously running power-shaft, a platen carriage, a platen on the carriage, letter-spacing mechanism for the carriage, printing means, power-operated means for returning the carriage, power-operated line-spacing mechanism for rotating the platen, a key for connecting both of said power-operated means with said continuously running shaft, and keys for connecting each of said power-operated means with the continuously running shaft independently of the other.

26. In a typewriting machine, the combination of a platen carriage, a platen on the carriage, escapement mechanism for letter-spacing the carriage normally locking the carriage against movement in either direction, type-carriers, key-operated carrier-selecting means, intermittently operating power-actuated means controlled by said selecting means for operating selected type-carriers and said escapement mechanism, means for releasing the carriage from the escapement mechanism for running movement in either direction by hand, and means for automatically locking said power-actuated means against operation when the carriage is released from the escapement.

27. In a typewriting machine, the combination of a platen carriage, a platen on the carriage, escapement mechanism for the carriage normally locking the carriage against movement in either direction, key-controlled power-operated printing means, power-operated means for advancing or returning the carriage with a running movement, means for releasing the carriage from the escapement mechanism for running movement, power-operated line-spacing means for rotating the platen adapted when put into action to operate said releasing means to release the carriage, a key for putting said second power-operated means into action to return the carriage and for simultaneously putting the line-spacing means into action, and a key for putting said second power-operated means into action to advance the carriage and for simultaneously actuating the carriage-releasing means independently of the line-spacing means.

28. In a typewriting machine, the combination of a platen carriage, a platen on the carriage, escapement mechanism for the carriage normally locking the carriage against movement in either direction, key-controlled power-operated printing means, power-operated means for advancing or returning the carriage with a running movement, means for releasing the carriage from the escapement mechanism for running

movement, power-operated line-spacing means for rotating the platen adapted when put into action to operate said releasing means to release the carriage, a key for putting said second power-operated means into action to return the carriage and for simultaneously putting the line-spacing means into action, a key for putting said second power-operated means into action to advance the carriage and for simultaneously actuating the carriage-releasing means independently of the line-spacing means, and a carriage-release key on the carriage adapted to operate said carriage-releasing means through the medium of the line-spacing means without rotating the platen.

29. In a typewriting machine, the combination of a platen carriage, a platen on the carriage, printing means, escapement mechanism for letter-spacing the carriage, power-operated means for advancing the carriage in letter-feed direction with a continuous running movement, means for releasing the carriage from the escapement, means for locking the printing means against operation, and a carriage-advance key controlling said power-operated means and connected to move said locking means to locking position and said releasing means to releasing position when said key is actuated to put the power-operated means into action.

30. In a typewriting machine, the combination of a platen carriage, a platen on the carriage, type-carriers, key-operated carrier-selecting means, intermittently operating power-actuated means controlled by the carrier-selecting means for actuating selected type-carriers, letter-feed mechanism for the carriage controlled by said carrier-actuating means, power-operated line-spacing means for rotating the platen, a lock for said carrier-actuating means movable to locking position by the line-spacing means, means for releasing the carriage from the escapement operable by said line-spacing means, and a key on the carriage connected to operate said carriage-releasing means and said lock for the carrier-actuating means through the medium of the line-spacing means without rotating the platen.

31. In a typewriting machine, the combination of a platen carriage, a platen on the carriage, type carriers, key-operated means for selecting said carriers, an intermittently operating power-driven actuator for actuating selected carriers, a lock for said actuator releasable by the carrier-selecting means, means for letter-spacing the carriage, means for imparting running movements to the carriage, and auxiliary locking means for automatically locking the actuator against operation during running movements of the carriage.

32. In a typewriting machine, the combination of a platen carriage, a rotatable

nation of a platen carriage, a rotatable platen on the carriage, a letter-spacing means for the carriage, power-operated means for rotating the platen for line-spacing, power-operated means for running the carriage in opposite directions, a carriage-return key controlling the carriage running means to return the carriage and operatively connected to put the platen-rotating means into action, a carriage-advance key controlling the carriage running means to advance the carriage, said advance key being ineffective to put the platen-rotating means into action.

33. In a typewriting machine, the combination of a platen carriage, a rotatable platen on the carriage, a letter-spacing means for the carriage, power-operated means for rotating the platen for line-spacing, power-operated means for running the carriage in opposite directions, a carriage-return key controlling the carriage running means to return the carriage and operatively connected to put the platen-rotating means into action, a carriage-advance key controlling the carriage-running means to advance the carriage, said advance key being ineffective to put the platen-rotating means into action, and a line-space key connected to put the platen-rotating means into action independently of the carriage-return key and the carriage-running means.

34. In a typewriting machine, the combination of a platen carriage, a rotatable platen on the carriage, key-controlled power-operated line-spacing means for rotating the platen, escapement mechanism for the carriage, and a key on the carriage connected to manually impart a movement to said line-spacing means ineffective to rotate the platen, and means operable by movement of the line-spacing means by said key on the carriage for releasing the carriage from the escapement mechanism.

35. In a typewriting machine, the combination of a platen carriage, a rotatable platen on the carriage, power-operated line-spacing means for rotating the platen, escapement mechanism normally locking the carriage against both advance and return movements, power-operated means for returning the carriage, a key in keyboard of the machine for putting said carriage returning means and said line-spacing means into action, means operable by the line-spacing means for releasing the carriage from the escapement upon actuation of said key, and a key on the carriage connected to manually impart movement to said line-spacing means for actuating the carriage-releasing means and to render the line-spacing means ineffective on the platen during such manual movement.

36. In a typewriting machine, the combination of a platen carriage, a rotatable

5 platen on the carriage, line-spacing means for rotating the platen embodying a ratchet wheel connected with the platen and a pawl and operating means therefor on the carriage for rotating said wheel and power-driven means for actuating said operating means, escapement mechanism for the carriage, carriage-releasing means operable through said power-driven actuating means 10 and the pawl-operating means, and a carriage-release key movable with the carriage connected to actuate the pawl-operating means and hold the pawl out of engagement with the ratchet wheel.

15 37. In a typewriting machine, the combination of a platen carriage, a rotatable platen on the carriage, line-spacing means for rotating the platen embodying a ratchet wheel connected with the platen and a pawl 20 and operating means therefor on the carriage for rotating said wheel and power-driven means for actuating said operating means, escapement mechanism for the carriage, carriage-releasing means operable 25 through said power-driven actuating means and the pawl-operating means, and a carriage-release key on the pawl adapted to actuate the pawl-operating means to release the carriage and hold the pawl out of engagement 30 with the ratchet wheel.

35 38. In a typewriting machine, the combination of a platen carriage, a rotatable platen on the carriage, escapement mechanism for the carriage normally locking the carriage against both advance and return movements, power-driven means for advancing or returning the carriage with a continuous running movement, advance and return keys controlling the direction of running of the 40 carriage by said power-driven means, means for releasing the carriage from the escapement mechanism, power-driven line-spacing means for rotating the platen connected to actuate said carriage-releasing means and 45 controlled by the carriage-return key, said advance key being connected to actuate the carriage-releasing means independently of the line-spacing means, and a line-space key connected to put the line-spacing means in 50 to action independently of the carriage-running means.

55 39. In a typewriting machine, the combination of a platen carriage, a rotatable platen on the carriage, escapement mechanism for the carriage normally locking the carriage against both advance and return movements, power-driven means for advancing or returning the carriage with a continuous running movement, advance and return keys 60 controlling the direction of running of the carriage by said power-driven means, means for releasing the carriage from the escapement mechanism, power-driven line-spacing means for rotating the platen connected to 65 actuate said carriage-releasing means and

controlled by the carriage-return key, said advance key being connected to actuate the carriage-releasing means independently of the line-spacing means, a line-space key connected to put the line-spacing means into 70 action independently of the carriage-running means, and a release key movable with the carriage connected to manually operate the line-spacing means to actuate the carriage-releasing means thereby, said release 75 key when actuated adapted to render the line-spacing means ineffective to rotate the platen.

40. In a power-operated typewriting machine, the combination of a power shaft, 80 a platen carriage, a platen, printing means, means for imparting running movements to the carriage, a frame shiftable to vary the relation between the platen and printing means for printing different case characters, means for shifting the frame, key-operated means for establishing a driving connection between said power shaft and the carriage running means, and key-operated means for establishing a driving connection between said power shaft and the frame shifting means, each of said connections 85 employing clutch members adapted for relative rotation while held in engagement by the key-operated means upon completion 90 of the movement of the parts driven thereby.

41. In a typewriting machine, the combination of a power-shaft, a platen carriage, carriage-returning means, line-spacing means, case-shifting means, separate friction slip clutches for connecting the carriage-returning means and the line-spacing means and case-shifting means with said power-shaft, and keys for operating said 100 clutches.

42. In a typewriting machine, the combination of a frame, a platen carriage, movable transversely of the frame, a movable tappet located substantially at the fore and aft center line of the frame for arresting the carriage, power-operated means for returning the carriage, margin and paragraph stop adjustable on the carriage transversely of the frame and adapted to engage said tappet to arrest the carriage, said tappet being 110 normally in position to be engaged by the margin stop and normally out of position to be engaged by the paragraph stop, a key for putting said carriage-returning means into action and moving said tappet into the 120 path of the paragraph stop, and a key for putting said returning means into action without shifting said tappet from normal position.

43. In a typewriting machine, the combination of a frame, a platen carriage movable transversely of the frame, a movable tappet located substantially at the fore and aft center line of the frame for arresting the carriage, power-operated means for re- 125 130

turning the carriage, margin and paragraph stops adjustable on the carriage transversely of the frame and adapted to engage said tappet to arrest the carriage, said tappet being normally in position to be engaged by the margin stop and normally out of position to be engaged by the paragraph stop, a key for putting said carriage-returning means into action and moving said tappet into the path of the paragraph stop, a key for putting said returning means into action without shifting said tappet from normal position, a rotatable platen on the carriage, and power-operated line-spacing means for rotating the platen adapted to be put into action by either of said keys.

44. In a typewriting machine, the combination of a frame, a platen carriage movable transversely of the frame, a movable tappet located substantially at the fore and aft center line of the frame for arresting the carriage, power-operated means for returning the carriage, margin and paragraph stops adjustable on the carriage transversely of the frame and adapted to engage said tappet to arrest the carriage, said tappet being normally in position to be engaged by the margin stop and normally out of position to be engaged by the paragraph stop, a key for putting said carriage-returning means into action and moving said tappet into the path of the paragraph stop, a key for putting said returning means into action without shifting said tappet from normal position, a rotatable platen on the carriage, power-operated line-spacing means for rotating the platen adapted to be put into action by either of said keys, and a third key for putting said carriage-returning means into action independently of the line-spacing means, said third key being disconnected from the tappet.

45. In a typewriting machine, the combination of a frame, a platen carriage movable transversely of the frame, margin and paragraph stops adjustable on the carriage transversely of the frame, a central tappet on the frame having two positions for engaging different ones of said stops during return of the carriage and adapted to arrest both stops at the longitudinal center line of the machine, means for returning the carriage, and means for positioning said central stop to cooperate with the margin stop or the paragraph stop at will, said tappet being arranged to slide on a yielding vertical thrust lug.

46. In a typewriting machine, the combination of a frame, a platen carriage on the frame, a platen on the carriage, a rack on the carriage extending transversely of the frame, a shaft on the frame, a pinion fixed on the shaft and meshing with said rack, power-driven means for rotating said shaft in either direction, an escapement wheel fixed

on said shaft, a pair of dogs for intermittently rotating said wheel for letter-spacing the carriage, one of said dogs normally locking said wheel against rotation, type, keys controlling the type, means for actuating the dogs when the type-controlling keys are operated, carriage advance and return keys, means operable by said keys for putting said power-driven means into action and controlling the direction of rotation of the shaft, and means for releasing said locking dog from the escapement wheel upon actuation of either the carriage-advance key or the carriage-return key.

47. In a typewriting machine, the combination of a main frame, a carriage frame having a front cross member carrying a scale and provided with a slot parallel with said scale, said slot and scale extending longitudinally of the front cross-member, means for guiding the carriage to move transversely of the main frame, a bar having notches along one edge thereof rigidly suspended from the front cross member of the carriage parallel with said slot, a plurality of stops slidable along said bar, a stop on the main frame adapted to be engaged by said slidable stops to arrest said stops at the longitudinal center of the main frame, horizontally swinging latches pivotally held to said slidable stops having noses adapted to engage in the notches in said bar, springs normally holding the latches in locking position, and finger-pieces held to said latches and extending upwardly through the slot in the cross-member, said finger-pieces being movable transversely and longitudinally of said slot and cooperating with said scale to indicate the positions of the stops.

48. An adjustable stop device for controlling the movement of traveling carriages of typewriting machines, comprising a flat sheet metal body portion having parallel longitudinal flanges formed with inwardly facing channels to receive the opposite edges of a notched stop-supporting bar, an arm extending from one edge of the body adapted to engage a part on the machine frame, a locking lever pivotally held to the body portion to swing in a plane parallel therewith, said lever extending longitudinally of the body outside of one of said longitudinal flanges, a projection carried by said lever adjacent its free end adapted to engage in notches in a bar on which the stop is mounted, a spring normally swinging the lever inwardly to locking position, an upstanding finger-piece carried by the lever, and a pointer formed on said finger-piece adapted to cooperate with a carriage scale.

49. In a typewriting machine, a power-driven carriage-returning mechanism, a line-spacing mechanism operable from the same power means, a key-controlled mechanism for putting the line-spacing mechanism

into operation independently, and two additional keys for putting the carriage-returning mechanism into operation, one of these latter keys being arranged to also put the 5 line-spacing mechanism into operation simultaneously with the carriage-returning mechanism.

50. In a typewriting machine, a power-driven carriage-returning mechanism, a 10 line-spacing mechanism adapted to be driven from the same power means, a key-controlled mechanism for putting the line-spacing mechanism into operation independently embodying a pivoted lever, a carriage-return lever adapted to put the carriage-returning mechanism into operation and simultaneously through said pivoted lever put the line-spacing mechanism into operation.

51. In a typewriting machine, a motor, a type-bar-actuating mechanism actuated by a spring and retracted by said motor, a letter-spacing mechanism operated by said type-bar-actuating mechanism, key-controlled devices for reversing the direction of letter-feed, and mechanism for giving the carriage a running movement in either direction through the medium of a part of the letter-spacing mechanism.

52. In a typewriting machine, a power-driven mechanism for operating the printing as well as the carriage-feeding devices, printing keys for putting said mechanism into action, a carriage-return mechanism put into action by key-controlled devices, and mechanism operable by said key-controlled devices for directly locking the carriage-feeding and printing mechanism against action during the return of the carriage.

53. In a typewriting machine, a power-driven mechanism for actuating the carriage-feed and the printing mechanism, this mechanism embodying a key-operated release device which when actuated releases the aforesaid mechanism and causes a power printing action, a key-controlled carriage-return mechanism, and a locking device for locking said release device when the carriage-return mechanism is put into operation, thereby preventing a printing operation during the return of the carriage irrespective of the point from which the carriage is returned.

54. In a typewriting machine, power-driven mechanism for driving the carriage in either direction, said mechanism embodying a pinion engaging a rack on the carriage, and mechanism for operating the pinion for letter-spacing independent of the remaining elements of the driving mechanism, this latter mechanism embodying a device for automatically locking the carriage at the end of each feeding movement.

55. In a typewriting machine, a carriage, a rack, a pinion engaging said rack, means for intermittently rotating said pinion to move the carriage for letter-spacing and comprising an intermittently operating reciprocal actuator, keys controlling the movement of said actuator, a constantly-operating rotary means for rotating the carriage-driving pinion in either direction, and keys to cause said rotary means to operate the pinion to run the carriage in either direction.

In testimony whereof I hereunto affix my signature.

MANSFIELD C. CRAWLEY.
